CLAIM

The ornamental design for a lady's golf glove, as shown and described.

DESCRIPTION

FIG. 1 is a front elevation view of a lady's golf glove showing my new design; and,

FIG. 2 is a rear elevation thereof.

The broken line showing of the palm and finger portions of a glove is for illustrative purposes only and forms no part of the claimed design.

The fragmentary criss-cross pattern shown in the drawing is understood to represent lace and is repeated uniformly through-out the areas shown.

The broken line showing of portions of the glove in FIGS. 1 and 2 is for illustrative purposes only and forms no part of the claimed design.
